UNITED STATES PATENT OFFICE.

FREDERICK WM. SCHMIDT, OF CONGER, MINNESOTA.

PORTABLE WASHSTAND.

1,113,495.

Specification of Letters Patent. Patented Oct. 13, 1914.

Application filed December 20, 1913. Serial No. 808,025.

To all whom it may concern:

Be it known that I, FREDERICK Wm. SCHMIDT, a citizen of the United States, residing at Conger, in the county of Freeborn 5 and State of Minnesota, have invented certain new and useful Improvements in Portable Washstands, of which the following is a specification, reference being had to the accompanying drawings.

10 This invention comprehends certain new and useful improvements in portable wash stands and has for its primary object to provide a device of this character which will be of extremely simple construction and cheap 15 to manufacture.

Another object is to provide a device of this character which will be composed of the minimum number of parts of simple formation and which will be properly braced, 20 whereby the device will be supported in upright position without the necessity of permanently attaching the same to a stationary support.

A further object is to provide a device of 25 this character which will be constructed in such manner that the height of the bowl or fluid container may be readily regulated, as desired.

A still further object is to generally improve and simplify the construction and operation of devices of this character and increase the efficiency and durability thereof, 30 without increasing the cost of manufacture of the same.

35 With the above and other objects in view, my invention consists in certain novel constructions, combinations, and arrangements of parts to be hereinafter more fully described, claimed, and illustrated in the accompanying drawings, in which:

Figure 1 is a side elevational view of the complete device; Fig. 2 is a front elevational view thereof; Fig. 3 is a fragmentary front elevational view; and Fig. 4 is a fragmentary 45 side elevational view, partly in section.

Referring more specifically to the drawings in which similar reference characters designate corresponding parts throughout the several views, 1 designates the standards 50 which are connected at their opposite ends by the upper and lower cross pieces 2 and 3, respectively, and which are supported in upright position by the inclined forwardly directed supporting legs 4 which are connected to the standards 1 and braced by the horizontal bars 5. The standards 1 are provided

with the upwardly directed teeth 6 on their forward longitudinal faces near their lower ends while the upwardly directed teeth 7 are provided upon the rear longitudinal edges of said standards adjacent the upper ends of the latter.

The bowl or fluid containing member 9 is supported upon the longitudinal frame members 10 having opposite outwardly directed upper edges 11 of said bowl or fluid containing member engaged upon said longitudinal frame members 10. It will be understood that the longitudinal frame members 10 are inwardly of the standards 1 and are connected at their rear ends by the rear transverse frame member 12, which is adapted for engagement with the upwardly directed teeth 7 on the rear longitudinal edges of said standards near the upper ends of the latter.

The longitudinal frame members 10 are connected at their forward ends by the forward transverse frame member 13, thereby retaining the longitudinal frame members in proper spaced relation. Pivoted to the forward ends of the longitudinal frame members 10 are the rearwardly and downwardly inclined frame supporting members 14 which are connected at their lower ends by the transverse connecting bar 15. The lower ends of the frame supporting members 14 are adapted for engagement with the first set of teeth 6 on the forward faces of the standards 1 adjacent the lower edges thereof.

The longitudinal frame members 10 are braced by the diagonal brace bars 17 having their upper ends connected therewith while their lower ends are connected to the frame supporting members 14.

A transverse bar 18 is provided between the bowl or fluid containing member 9 and the standards 1 and has its opposite ends connected to the longitudinal frame members 10. By grasping this transverse bar 18 and moving the supporting frame inwardly or rearwardly toward the standards 1, the rear transverse frame member 12 will be disengaged from the teeth 7 and the frame, together with the frame supporting members 14 and the bowl or fluid containing member 9 may be raised or lowered to the desired position and the rear transverse frame member 12 again engaged with the teeth 7.

From the foregoing, it will be clearly apparent that I have provided a portable wash stand of extremely simple construction and

which may be readily placed in position and properly adjusted to place the bowl or fluid containing member in horizontal position and the proper distance from the surface 5 upon which the standards and supporting legs rest. It will also be evident that the device may be readily and cheaply manufactured and may, if desired, be employed as a sink or the like, as well as a wash stand.

10 While I have shown the preferred embodiment of my invention, it will be understood that minor changes in the details of construction and arrangement of parts may be made within the scope of the appended claim 15 without departing from the spirit of my invention or sacrificing any of the advantages of the same.

What I claim is:—

20 A device of the character described comprising standards having teeth adjacent

their opposite ends, the teeth of each of the standards at one extremity being reversely disposed relative to the teeth at the opposite extremity, a supporting frame comprising spaced bars disposed inwardly of the standards and having adjacent extremities connected by a transverse bar, the extremities whereof being projected beyond the parallel bars and adapted to engage the teeth at the upper extremities of the standards, bracing 25 means for the supporting frame engageable with the notches at the lower end of the standards.

In testimony whereof I hereunto affix my signature in the presence of two witnesses. 30

FREDERICK WM. SCHMIDT.
